BARBECUE GRILL

Trace Christenson, Jr., and Robert L. Gallup, Niles,
Mich., assignors to The Majestic Company, Inc.,
Huntington, Ind., a corporation

Filed Mar. 17, 1960, Ser. No. 59,775

Term of patent 14 years

(Cl. D81—25)

FIG. 1

Fig. 1 is a perspective view of a barbecue grill, showing our new design.

Fig. 2 is a top plan view thereof.

Fig. 3 is a left side elevation view thereof.

The essential features of the design reside in the portions shown in full lines.

We claim:

The ornamental design for a barbecue grill, as shown and described.
